SIMULATED BASEBALL GAME

Albert Schlappa, Brookfield, Ill., assignor to Chicago Dynamic Industries, Inc., Chicago, Ill., a corporation of Illinois

Application August 4, 1958, Serial No. 752,830

14 Claims. (Cl. 273—88)

My invention relates to a simulated baseball game.

An object of the invention is to provide a novel arrangement for simulating the movement of a simulated baseball over a playing surface presenting a simulated baseball diamond, thereby to add greatly to the attraction and amusement afforded by the game apparatus.

Another and equally important object of the invention is to provide a movable carriage having a light source moved by the carriage beneath a translucent simulated baseball field whereby to simulate hits, outs, and strikes which occur in the conventional baseball game.

Yet another and important object of the invention will be found in the novel construction for moving a light source simulating a baseball over the area of the simulated baseball field.

Another and equally important object of the invention is to provide in a simulated baseball game a "pitching" switch and a "batting" switch, the "pitching" switch controlling a circuit for the baseball simulated light source and the "batting" switch controlling the circuit which results in a "hit," a "strike" or "out," both switches being under the manual control of the player and therefore calling for the exercise of the skill of the player in the playing of the game.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the simulated baseball game embodying the invention;

Fig. 2 is a plan view taken in the direction of line 2—2 of Fig. 1;

Fig. 3 is a sectional detail view taken substantially on the line 3—3 of Fig. 2;

Fig. 4 is an enlarged view of the switch structures as illustrated on the left-hand side of Fig. 3;

Fig. 5 is a plan view of the switch wiper plate embodied in the invention;

Fig. 6 is a perspective view of the switch assembly as seen in the left-hand portion of Fig. 3;

Fig. 7 is a fragmentary perspective view of a wiper switch assembly embodied in the invention;

Fig. 8 is a fragmentary sectional detail view taken substantially on line 7—7 of Fig. 2;

Fig. 9 is a schematic circuit diagram embodied in the invention.

The several objects of my invention are accomplished by the preferred form of construction shown in the accompanying drawings.

Referring more particularly to Fig. 1, the mechanism incorporated in my improved baseball game is arranged in a cabinet 10 having a transparent top wall 11 and a front ledge 12 on which are mounted the batter switch 13 and the starting switch 14. Each of these switches includes a hand-operated button 15 and 16, respectively.

2

Within the cabinet 10 and in spaced relation with and beneath the transparent cover 11 is a partition 16 having a simulated baseball diamond 15 thereon. The partition 16 provides a playing surface and is of a translucent material, the degree of density of which is such as permits the penetration therethrough of a spot of light but otherwise conceals anything therebeneath.

On the partition 16 are positioned manikins 14 simulating baseball players.

10 Within the cabinet 10 and beneath the partition 16 and disposed substantially in spaced parallel relation with respect thereto is a mounting plate 17.

Carried by the mounting plate 17 at one end thereof (Fig. 3) is a pintle bolt 18. This bolt projects through an opening formed in a horizontal flange 19 of plate 20.

15 The plate 20 at its upper end portion 21 (Fig. 3) is secured by means of bolts 22 to one end portion of a beam 23. This beam 23 is U-shaped in cross section to provide spaced parallelly extending flanges 24.

20 To the upper flange 24 (Fig. 7) there is secured as at 26 an elongated plate 25 which extends the full length of the upper flange 24 of the beam 23. Along the opposite longitudinal edge portions 27 of the plate 25 are track plates 28. The bar 25 is preferably formed of wood, whereas the track plates 28 are of metal and serve to protect the plate 25 from wear. The opposite end portions of the track plates 28 are curved downwardly as at 29 for reasons which will be apparent hereinafter. The end 30 of the beam 23 has an extension secured thereto in any suitable manner, which provides parallel fingers 31 between which is mounted as at 32 a roller 33.

35 At the pivoted end of the beam 23 there is secured to the plate 20 (Fig. 2) a supporting platform 34 on which is mounted an electric motor 35. The shaft 36 of such motor 35 carries a roller 33' of the same size as the roller 33 and in spaced alignment with respect thereto. The roller 33' is disposed between the curved end portions 29 of the track plates 28. Extending around the rollers 33 and 33' and operable thereby is a continuous flexible belt 37. Secured to the belt 37 (see Fig. 7) is a carriage 38 comprising a horizontal plate 39 carrying an electric socket 40 for an electric light bulb 41.

40 The carriage 38 also includes wheels 42 (Figs. 6 and 7) which have tractive engagement with the track plates 28 and which wheels support the carriage 38 for movement along the top surface of the plate 25. The carriage at one side edge thereof has an upstanding flange 39 (Figs. 6-7). Extending laterally from the flange 39 is a pin 43.

45 The beam 23 and plate 25 provide together a boom supporting the belt for rotation therealong together with carriage 38. At the left-hand end portion of the boom as seen in Fig. 3, there projects downwardly therefrom a U-shaped support 44 comprising spaced legs 45 (Fig. 2) each carrying a wheel 46. Each wheel rides upon the edge portion 47 of a plate 48 secured to the mounting board 17. By this structure the end of the boom opposite the pivoted end portion thereof is supported for oscillatory movement across the mounting board 17 and beneath the playing field 15. The means for oscillating the boom comprises an electric motor 48 (Fig. 2). This motor has a shaft 49 to which one end of a link 50 is secured. The opposite end portion of the link 50 is connected as at 51 to a driving link 52 having connections as at 53 to the supporting platform 34.

55 The arrangement of the structure thus far described is such that when the motor 35 is energized the belt 37 will be rotated. Rotation of the belt 37 will move the carriage 38 therewith.

The carriage 38 includes a shield 54, as best seen in

Fig. 6. This shield 54 is mounted over the electric light bulb 41 and has in its horizontal wall 55 a relatively small opening 56 formed therein. The light beam which is directed through this opening 56, upon striking the playing field 51, will be of sufficient area to simulate a baseball moving over the playing surface.

Upon operation of the motor 48, the boom will be oscillated over the mounting plate 17 in a manner and for the reasons hereinafter more fully set forth.

Mounted on the left-hand end portion of the beam 23 are spaced brackets 57, the upper end portions of which carry an elongated plate 58 which extends above and to the side of the adjacent long edge of the belt 37.

Mounted on this plate 58 are switch elements 59, 60, 61 and 62. The switch elements 60, 61 and 62 each 10 constitute a single switch comprising a pair of switch blades 63, 64 and 65, respectively.

The switch element 59 comprises two switches 66 and 67 each comprising a pair of switch blades 68 and 69, respectively. Each of the switch elements 59 to 62 inclusive includes an actuating finger 70, 71, 72 and 73, respectively. These actuating fingers are adapted to actuate the switch blades for reasons hereinafter more fully set forth.

At the opposite end portion of the boom there are provided spaced brackets 74 carrying therebetween a plate 75. On this plate 75 (Fig. 5) are mounted switch elements 76, 77, 78, 79, and 80.

The switch elements 76 and 80 each comprise a single switch 81 and 82 including switch blades 83. The switch elements 77, 78 and 79 each comprise two switches 84 and 85. The switches of the switch elements 76 to 80 inclusive are each actuated by the actuating fingers 86, 87, 88, 89 and 90.

The actuating fingers 70 to 73 and 86 to 90 are disposed along the side edge of the belt 37 in the path of the finger 43 carried by the carriage 38 for reasons which will be more fully explained hereinafter.

On the mounting plate 17 is mounted a non-conductive plate 91 (Figs. 6 and 8). This plate carries a plurality of contact heads 92, 93 and 94 and also contact strips 95 through 99.

Carried by the lower flange 24 of the beam 23 is a downwardly inclined plate 101 (Fig. 6), the outer end portion of which has a non-conductive strip 102 secured thereto. Secured to and insulated from the lower portion of the plate 102 are contact fingers 103 through 107 which are adapted to engage the contact heads 92 through 94 and the contact strips 95 through 99 according to the position of the boom with respect to the mounting plate 17 and the playing field 16.

In Fig. 4 I have illustrated schematically a suggested circuit for controlling the operation and playing of the game. In reference to this circuit, switches 59 through 62 are designated respectively as "Hits," "Single Hit and Outs," "Infield Outs" and "Carriage Stop." The switch elements 76 through 80 are designated as "Strike Out," "Left Field," "Center Field," "Right Field," and "Strike Out," respectively. These designations may change in the event that the manufacturer of the game should so desire.

As it is desirous that this apparatus be coin-controlled, I provide a coin switch 109 which coin switch energizes a start relay 110. This start relay will close a self-locking start switch 111, which in turn will cause energization of a pitch control motor 112. This pitch control motor 112 will cause a wiper arm 113 to move over the pitch mixer disc 114.

On this disc 114 there are a series of contacts connected to a line 115 which line is in turn connected to a right field return relay 116. Other contacts on the disc 114 are connected to line 117 which line is in turn connected to a left field return relay 118. The game is now conditioned for the first play.

The player will depress the button 16 which will close a starting or pitch switch 14. The closure of the pitch switch 14 will energize a pitch relay 119. This pitch relay 119 will close associated switches which will herein be identified as they appear in the circuit of operation. The energization of the pitch relay 119 is from line A, through wiper arm 104, contacts 120, the now closed pitch switch 14, through the pitch relay 119 to line B.

The energization of the pitch relay 119 will close a pitch relay switch 121. This pitch relay switch 121 energizes the wiper arm 113 as it passes over disc 114. Thus if the wiper arm 113 is on a contact connected to line 117, the right field return relay 116 will be energized. The energization of the right field return relay 116 will close a right field return relay switch 122. This will energize an armature coil 123 of a servo amplidyne motor 48. The right field return relay 116 will also close a right field return relay switch 124 which will complete a circuit to the directional motor 48 which will cause the boom to move in one direction.

Simultaneously with the energization of the motor 48, a belt drive motor 35 is energized. This belt drive motor 35 is caused to be energized by the closing of a pitch relay switch 125. This causes the carriage 38 to move from its original position toward the switches 76 through 80.

As the carriage approaches the switches 76 through 80, the boom is moved in a manner hereinbefore described and thus there is imparted to the movement of the carriage a slight curvature through a longitudinal line extending from its original position toward the switches 76 to 80. The direction of this curving effect is dictated by the direction of initial energization of the motor 48, which is the result of the contact the wiper arm 113 is on, when the pitch switch 14 is closed. The player will then depress the batter button 15 in turn closing a bat switch 13. If when the bat switch 13 is closed, the carriage 38 has caused any of the switches 76 through 80 to be closed, certain relays will be caused to be energized. Let us say for an example, that when the bat switch 13 is closed, the carriage 38 has caused the switch 77 to be closed. The closure of the switch 77 will energize a left field hit relay 126. The energization of the left-field hit relay 126 will close a left-field hit relay switch 127 which is also in circuit to the right-field return relay 116. Thus this relay 116 will be maintained energized notwithstanding that the left-field hit relay 126 has opened a normally closed left-field hit relay switch 128 which has disrupted the circuit to the wiper arm 113. As the right-field return relay 116 has been originally energized and the right-field return relay switch 124 was closed by the initial energization of the relay 116, the closing of the left-field hit relay switch 127 maintains energization of the motor 48 thus causing the boom to move in the direction of the left field. As the boom moves, the wiper arms 103 through 107 will move over the plate 91 and the wiper arms 104 and 105 will pass on to the plates 97 and 99 respectively. Thus the motor 48 is continually energized. The motor 48 will thus move to its extreme left position and through the linkage 50 through 53 will be caused to be moved from such extreme left position back to the center position at which time the wiper arms 104 and 105 will pass off the strips 97 and 99 respectively, deenergizing the motor 48.

By energizing the left field hit relay 126, we have closed a left field hit relay switch 129, which causes the belt drive motor 35 to reverse itself thus moving the carriage 38 along the boom in a direction toward switches 59 and 62. If the carriage 38 should close switch 61 while the wiper arm 107 is on certain contacts 94, an out will be indicated. If the carriage 38 should close switch 60 in its movement over the boom while the wiper arm 106 was on certain contacts 93 either a hit or an outfield out would be indicated. The selection of the contacts 93

which indicate a hit or an out may be at the discretion of the manufacturer.

I have provided an out step-up coil 140 which is momentarily energized by the closing of either of the out switches 61 or 60. This out step-up coil 140 may also be energized by a third strike contact on disc 141. The wiper arm 142 of the disc 141 is advanced by energization of a strike step-up coil 143. This coil 143 is energized every time the strike switches 76 and 81 are closed.

The coil 140 will advance a wiper arm 144 over an "out" disc 145, until it contacts the third out contact, which energizes the game-over relay 138.

If the carriage 38 closes switch 59 while the wiper arm 103 is on a contact 92 of the plate 91, an extra base hit will be indicated.

It should be pointed out that when the left field hit relay 126 was energized, it opened a normally closed left field hit switch 130 which was in series with the pitch relay switch 125 that initially energized the belt drive motor 35.

The same result would follow if the bat switch 13 was closed when the carriage 38 was in engagement with the switch 78 which in turn would cause energization of a center field hit relay 131. If the carriage 38 was in engagement with and closing the switch 79, a right field hit relay 132 would be energized.

When a "hit" is made the relay energized will open a normally closed switch thus deenergizing the remaining hit switch. Relay 126 will open relay switch 126', relay 131 will open relay switch 131', and relay 132 will open relay switch 132'.

With respect to the direction of movement of the boom, I provide a left-field return relay 133 which functions exactly like the right-field return relay 116 which relay 133 would close a relay switch 134 for directing the movement of the boom by energizing the motor 48. Such left-field return relay 133 would be maintained energized by a right-field hit which causes the energization of the right-field hit relay 132 which in turn would close a right-field hit relay switch 135, thus energizing the left-field return relay 133. When the carriage 38 moves in the direction of the switches 59 through 62, it will ultimately close the last switch 59 which will cause energization of a return to pitch position relay 136. The energization of the return to pitch position relay 136 closes a return to pitch relay switch 137 causing the drive belt motor 35 to be energized so as to cause the carriage 38 to reverse its movement in the direction of the switches 76 to 80. The belt drive motor 35 is energized until the carriage stop switch 62 is closed by the movement of the carriage.

In the event that when the pitch switch 14 is closed and the belt drive motor 35 is energized and the carriage 38 begins its movement toward the switches 76 through 80, the bat switch 13 is not closed. The carriage will close switch 80, which will indicate a strike. The belt drive motor 35 will continue to be energized until the carriage makes a complete cycle about the boom and closes the stop switch 62.

In the event that the bat switch 13 is closed when the carriage 38 is closing the switch 76, a strike will also be indicated and the carriage will follow the same course as above described. The game is continued to be played until a third out is made at which time the game over relay 138 is energized which will open a game-over relay switch 139 disrupting the circuit to the game.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, and a member on said carriage for engaging said switch to actuate the same.
2. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, and an electric circuit scanning means including a stationary element and a movable element, the latter carried by and movable with said carriage to render effective said switch when closed by said last-named member and when said boom is in a predetermined position with respect to said transparent member.
3. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving means including a switch effective to energize said circuit to reverse the direction of movement of said carriage relative to the boom, said circuit also including a switch ineffective when said first switch is effective but effective, when said first switch is ineffective, to energize said carriage moving motor means to move said carriage through a cycle of revolution with respect to said boom, and means on said carriage engageable with said switches for independently actuating the same.
4. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to

energize said circuit to reverse the direction of movement of said carriage relative to the boom, a member on said carriage for engaging said switch to actuate the same, and an electric circuit scanning means including a stationary element and a movable element, the latter carried by and movable with said carriage to render effective either of said first or second mentioned switches when closed by said last-named member and when said boom is in a predetermined position with respect to said transparent member.

5. A simulated baseball game comprising a horizontally disposed transparent member having on one side thereof a simulated baseball diamond, a boom disposed beneath and in parallel relation with respect to said member, electric motor means for oscillating the boom relative to said member in a plane parallel to the plane of the adjacent surface of said transparent member, a carriage mounted for movement along and around the boom in its longitudinal direction, motor means for moving the carriage, a light source on said carriage for directing a 10 spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, an electrical circuit for said boom oscillating electric motor means and including a manually operated push button switch to initially energize said 15 electric motor means, and means for holding said oscillating motor means energized for a predetermined time.

6. A simulated baseball game comprising a horizontally disposed transparent member having on one side thereof a simulated baseball diamond, a boom disposed beneath and in parallel relation with respect to said member, electric motor means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, an electrical circuit for said boom oscillating electric motor means and including a manually operated push button switch to initially energize said electric motor means, means for holding said oscillating motor means energized for a predetermined time, and an electric circuit scanning means including a stationary element and a movable element, the latter carried by and movable with said carriage to render effective either of said first or second mentioned switches when closed by said last-named member and when said boom is in a predetermined position with respect to said transparent member.

7. A simulated baseball game comprising a horizontally disposed transparent member having on one side thereof a simulated baseball diamond, a boom disposed beneath and in parallel relation with respect to said member, electric motor means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, said circuit also including a switch ineffective when said first switch is effective but effective, when said

first switch is ineffective, to energize said carriage moving motor means to move said carriage through a cycle of revolution with respect to said boom, means on said carriage engageable with said switches for independently actuating the same, an electrical circuit for said boom oscillating electric motor means and including a manually operated push button switch to initially energize said electric motor means, and means for holding said oscillating motor means energized for a predetermined time.

8. A simulated baseball game comprising a horizontally disposed transparent member having on one side thereof a simulated baseball diamond, a boom disposed beneath and in parallel relation with respect to said member, electric motor means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, an electrical circuit for said boom oscillating electric motor means and including a manually operated push button switch to initially energize said electric motor means, means for holding said oscillating motor means energized for a predetermined time, and an electric circuit scanning means including a stationary element and a movable element, the latter carried by and movable with said carriage to render effective either of said first or second mentioned switches when closed by said last-named member and when said boom is in a predetermined position with respect to said transparent member.

9. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage including a shield having an opening for directing a spot of light upon said adjacent surface of said transparent member to simulate a baseball, an electrical circuit for said carriage moving motor means including a switch effective to energize said circuit to reverse the direction of movement of said carriage relative to the boom, and a member on said carriage for engaging said switch to actuate the same.

10. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage including a shield having an opening for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, and an electric circuit scanning means including a stationary element and a movable element, the latter carried by and movable with said carriage to render effective said switch when closed by said last-named member and when said boom

is in a predetermined position with respect to said transparent member.

11. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage including a shield having an opening for directing a spot of light upon said adjacent surface of said transparent member to simulate a baseball, an electrical circuit for said carriage moving means including a switch effective to energize said circuit to reverse the direction of movement of said carriage relative to the boom, said circuit also including a switch ineffective when said first switch is effective but effective, when said first switch is ineffective, to energize said carriage moving motor means to move said carriage through a cycle of revolution with respect to said boom, and means on said carriage engageable with said switches for independently actuating the same.

12. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage including a shield having an opening for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, and an electric circuit scanning means including a stationary element and a movable element, the latter carried by and movable with said carriage to render effective either of said first or second mentioned switches when closed by said last-named member and when said boom is in a predetermined position with respect to said transparent member.

13. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted

for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, an electric circuit scanning means including a stationary element and a movable element, the latter carried by and movable with said carriage to render effective said switch when closed by said last-named member and when said boom is in a predetermined position with respect to said transparent member, said electric circuit including a second switch operative by said last-named member to energize the circuit when the carriage has reached a predetermined point with respect to said boom.

14. A simulated baseball game comprising a horizontally disposed transparent member having on one side thereof a simulated baseball diamond, a boom disposed beneath and in parallel relation with respect to said member, means for oscillating the boom relative to said member in a plane parallel to the plane of the adjacent surface of said transparent member, a carriage mounted for movement along and around the boom in its longitudinal direction, motor means for moving the carriage, a light source on said carriage for directing a spot of light upon said adjacent surface of said transparent member to simulate a baseball, an electrical circuit for said carriage moving motor means including a switch effective to energize said circuit to reverse the direction of movement of said carriage relative to the boom, a member on said carriage for engaging said switch to actuate the same, and an electric circuit scanning means including a stationary element and a movable element, the latter carried by and movable with said carriage to render effective either of said first or second mentioned switches when closed by said last-named member and when said boom is in a predetermined position with respect to said transparent member, said electric circuit including a second switch operative by said last-named member to energize the circuit when the carriage has reached a predetermined point with respect to said boom.
